UNITED STATES PATENT OFFICE.

JOHN B. WATLING, OF CHICAGO, ILLINOIS.

DESIGN FOR A SCALE-CABINET.

48,051.

Specification for Design.

Patented Oct. 26, 1915.

Application filed September 26, 1914. Serial No. 863,775. Term of patent 7 years.

To all whom it may concern:

Be it known that I, JOHN B. WATLING, a citizen of the United States, residing in the city of Chicago, State of Illinois, have invented a new, original, and ornamental Design for Scale-Cabinets, of which the following is a specification, reference being had to the accompanying drawing, forming part thereof.

The figure is a perspective view of a scale cabinet showing my new design.

I claim:

The ornamental design for a scale cabinet, as shown.

JOHN B. WATLING.
